UNITED STATES PATENT OFFICE.

JOHN C. LONG, OF MECHANICSBURG, PENNSYLVANIA.

REGENERATIVE HOT-BLAST APPARATUS.

SPECIFICATION forming part of Letters Patent No. 248,484, dated October 18, 1881.

Application filed March 31, 1880. (No model.)

To all whom it may concern:

Be it known that I, JOHN C. LONG, a citizen of the United States, residing at Mechanicsburg, in the county of Cumberland, and State 5 of Pennsylvania, have invented new and useful Improvements in Hot-Blast Ovens, of which the following is a specification.

This invention relates to certain improvements in regenerative hot-blast apparatus for 10 heating a blast of air, gases, or vapor to be supplied to metallurgical furnaces for intensifying the action therein.

Heretofore it has been customary to heat regenerative hot-blast apparatus by burning 15 therein combustible gas having a temperature equal to that which it has when leaving the blast-furnace or other source of supply less than lost during its passage to the hot-blast apparatus. This temperature in the case of the 20 waste gases of the blast-furnace is about 300° or 400° as it leaves the furnace, less the loss of transmission. The air used for combustion is drawn into the apparatus by means of the draft of a very high chimney, and is used at the 25 temperature of the atmosphere, except in one case in which it is claimed to be heated by passing through passages or channels in the partition-walls of the apparatus.

The above methods are objectionable be- 30 cause the temperature or intensity of the heat of the blast is limited, on account of using the combustible gas at so low a temperature and burning it with air drawn in by a tall chimney, by which means no intense combustion of the 35 gas or proper distribution of the products of combustion can be produced. Further, on account of the method of heating the air for combustion it is evident that it can attain no very great temperature, as the passage in which it is heated cannot be made sufficiently large. The quantity of air necessary for combustion 40 bears quite a large ratio to the quantity of blast that an oven can heat, and it is manifest the surfaces of the passages do not bear a similar ratio to the surfaces of the flues of the oven.

The object of my invention is to provide a regenerative hot-blast apparatus by means of which a blast of air, gases, or vapors may be obtained whose temperature is only limited by 45 the resistance of the refractory materials com-

posing the apparatus, thus greatly facilitating and economizing metallurgical operations now employed and rendering useful some heretofore considered impracticable. In most metallurgical operations it is a great intensity of 55 heater temperature that is desired; for a metal may be exposed to any quantity of heat without fusing, provided the temperature be below its fusing-point, while on the contrary a short exposure to a temperature but slightly above 60 its melting-point will fuse it, although in the latter case it is exposed to a much smaller quantity of heat, but that of greater intensity, hence greatly economizing fuel and facilitating the operation; and, as in the blast-furnace, the quantity of fuel over and above that necessary to reduce the ore and carbonize the metal is used, mainly, for fusing the metal and slag, it follows that the more intensely the 65 blast is heated the less fuel it will be necessary 70 to burn in the hearth of the furnace, and as a blast can be produced by my apparatus whose temperature is only limited by the resistance of the refractory materials of the ovens, hence by its use a blast-furnace can be worked nearer 75 the theoretical minimum of fuel than heretofore, and as a consequence of the decrease in the fuel the necessary air-supply is also reduced and the working capacity of the furnace increased, owing to the greater space for 80 charges other than fuel, thus materially reducing the cost of production. By using a very intensely heated blast greater control of the furnace is obtained and more refractory ores and fluxes can be used, thus making valuable 85 heretofore useless materials.

To this end the invention consists in the combination, with the peculiarly-constructed ovens in which the blast of air, gases, or vapors are heated prior to passing to the furnace, of similar supplementary ovens or heaters for heating the combustible gas which is subsequently burned in both the blast-ovens and gas-heater, for the purpose of intensely heating them, as is more fully explained 95 hereinafter; and it also consists in the connections by which the gas-heaters are connected to the ovens and with each other, whereby the highly-heated combustible gas may be introduced into the oven or gas-heaters to be 100

burned therein; and it further consists in introducing into the ovens and gas-heaters of a forced blast of highly-heated air from the hot-blast main or parts in free communication with it, thus burning the combustible gases therein by a forced hot blast to intensify the combustion thereof, and produce an equable distribution of the hot products of combustion and a more equal heating of the ovens and heaters, and at the same time decreasing the amount of draft necessary to be produced by the chimney; and it also consists of the air-connections employed for this purpose.

In the drawings, Figure 1 represents a vertical longitudinal section through the oven-connection and gas-heater, showing the valves closed and the manner of forming the ovens, gas-heaters, and the arranging of the flues into a set in a decreasing series from the combustion-chambers and the top and bottom chambers or flues, and method of removing the dust. Fig. 2 represents a horizontal section on the line $x-x$ of Fig. 1, showing the combustible-gas connection and the cold-blast and chimney-connections. Fig. 3 represents a horizontal section on the line $y-y$ of Fig. 1, showing the hot-air connections and form of the oven and heaters. Fig. 4 represents a transverse vertical section through the combustion-chamber of the ovens on the line $y'-y'$ of Fig. 3, showing their construction. Fig. 5 represents a transverse vertical section through the combustion-chamber of the gas-heaters on the line $z-z$ of Fig. 3.

In carrying out the invention, where a continuous blast is desired at least two ovens are employed for heating the blast supplied to the furnace. In connection with the ovens, as above, two or more gas-heaters are used, and in a similar manner to the ovens, as above.

In the following description but two ovens for heating the blast are combined with two gas-heaters for heating the combustible gas.

The letters B' B indicate the ovens for heating the blast, and are rectangular in form and constructed of fire-brick or other suitable refractory materials, and whose walls are supported by circular or elliptical segmental walls of ordinary brick-work and incased with sheet-iron, or the space between the oven and the sheet-iron casing may be filled with cinder, loam, or broken bricks, &c. The sheet-iron casing is suitably strengthened at the angles to resist the strain put upon it by the pressure of the blast and the expansion of the oven. The roof is also covered with sheet-iron, put on in strips corresponding with the width of the roofs of the flues and having upturned flange-like edges bolted together or held down in place by girders passing over the middle of each flue and fastened at each end to the side casing of the oven. The interior of each oven is divided into two parts—viz., D^2 , the combustion-chamber, and C^5 , the regenerator—by the wall B^5 , which extends from the bottom to near the top, only allowing sufficient room for

the horizontal flue H^5 . The lower part of the combustion-chamber D^2 is contracted by the walls E^5 , Fig. 4, which are run up square to the level of the perforated air-cylinder O^2 and blocks S^2 , and from thence they rapidly taper off, for the purpose of producing a more perfect combustion of the gas and for increasing the draft by means of the diverging jets of air from the cylinders and blocks, as well as evenly distributing the flame and gaseous products of combustion to the several independent compartments of the oven hereinafter mentioned.

The upper termination of the tapering wall is indicated by line d in Fig. 1. The air-cylinder O^2 is placed in the combustion-chamber D^2 so that it shall be midway between the air-blocks S^2 , at the angle of the side walls, E^5 , in order to divide the combustible gas equally.

The cylinder is perforated by a number of circular holes, P' , Fig. 4, so arranged that no two adjacent ones shall be in the same vertical plane, thus, as it were, breaking joints, so that the jets of air issuing therefrom shall have different vertical angles, the lower ones being

horizontal, or nearly so, the others at different angles, so as to equally distribute the flame throughout the chamber D^2 . The air-blocks S^2 are placed at the angles of the walls E^5 , and are provided with holes arranged in a similar

manner to those in the cylinder O^2 , but so that the jets issuing from them shall not strike those from the cylinder O^2 , but shall pass between or interlace with them, thus having the ascending combustible gas divided by the cylinder O^2 , and each current passing between two

series of air-jets, by the lower of which the gas is mixed with air, and then burned by the upper ones, thus having it consumed under circumstances the most favorable for the production of a most intense heat.

The cylinder O^2 and air-blocks S^2 communicate with the hot-air main L' or parts in free communication with it by means of the pipes P^2 in the former case and the several pipes T^2 in the latter, having the regulating-valves R^2 and U^2 respectively, which, when once properly set, always remain open during the operation of the oven, both when it is heating the blast and when it is burning gas. The air-blocks lying on the adjacent sides of the ovens may be connected directly by the pipe S^4 having valve S^5 , which is operated similar to R^2 .

The lower part of the chamber D^2 is provided with an opening for the hot-blast and hot-gas connection M^2 and for cold-gas connection V^2 , as well as the opening M for the removal of dust.

The upper part of the combustion-chamber D^2 is provided with a series of flues, E , Fig. 4, communicating with the regenerator C^5 , and formed by the roof-supporting partition-walls, which walls extend from the front to the back and from the top to the bottom of the ovens, except in the combustion-chamber D^2 , in which they extend only to the top of the sloping walls E^5 . The oven is thus divided into several in-

dependent compartments, which, in the regenerator C⁵, are divided by the walls F⁵ into flues E², arranged in sets forming a decreasing series from the combustion-chamber D², and the 5 spaces H⁵ and I⁵ at the top and J⁴ and K⁴ at the bottoms are formed by having the walls F⁵ to neither reach the top or bottom except in that forming the last flue of the first set, which extends to the top, and that forming the last 10 flue of the second set, which extends to the bottom, thus, for example, having four flues in first set, three in the second, and two in the third set, and forming a decreasing series from the combustion-chamber or an increasing 15 series from the cold end; and as the gaseous products of combustion contract while cooling the surfaces over which they pass and impart their heat, as well as the capacity of the passages and absorbing materials, decrease in proportion, and, conversely, as the blast expands as it is heated the capacity of the passages and heat-imparting materials and surface over which it passes increases, thus in either case 20 maintaining a uniform velocity, and having the absorbing and radiating surfaces and capacity 25 of the passages or sets of flues and quantity of materials proportioned to the volume of the products of combustion or blast passing through each part of the oven, and in addition thereto 30 the products of combustion as well as the blast are, by means of the several independent compartments formed by the walls L and containing the above-described series of flues, compelled to pass through the oven in independent 35 currents, thus obtaining a more equable heating of the oven and distribution of the blast to be heated, and consequently very greatly increasing the efficiency of the apparatus.

The letter M indicates a small transverse 40 channel in the inverted circular bottom of the chambers J⁴ and K⁴, extending through the oven and closed by suitable doors or means at the sides of the oven, for the purpose of removing the dust. Similar opening is made in 45 the combustion-chamber D². The lower parts of each last set of flues in the several independent compartments communicate with each other and also communicate with the chimney D' by means of the openings T⁴ in the walls 50 L, and the connections H², and the pipe G², which is provided with the valve I², by which means communication can be cut off or established at will. They also communicate with the cold-blast-supply pipe K², by openings T⁴, 55 connection H², and cold-blast pipe K², having valve L², by which communication can be established or cut off at will.

The ovens or combustion-chambers D² communicate with the hot-gas-supply main E' by 60 means of the pipe M², provided with valve N², for the purpose of receiving hot gas for combustion, and with the hot-blast main L', by means of the pipe M², vertical pipe U', and provided with the valve O², and branch B², for the 65 purpose of carrying the hot blast from the oven to the hot-blast main L'.

All of the pipes or connections and mains are lined with fire-brick, with the exception of the cold-blast-supply pipe.

The gas-heaters are constructed similarly to 70 the ovens internally, but may be made smaller by decreasing the number of compartments or the number of flues, or both. In the drawings they are made smaller by decreasing the number of flues.

The combustion-chamber may be constructed like those of the ovens, or they may be made with either the air-cylinders or air-block alone. In any case their connection to the hot-air main for receiving hot air for combustion is made 80 by pipes R', having valves T', or pipe N', having valve O', by which communication can be established or cut off at will.

The letter E' indicates the hot-gas main, into 85 which the gas-heaters deliver the gas which they have heated through the hot-gas-connection pipe G', provided with the valve H, by which communication can be established or cut off. The gas-heaters also communicate with the main E' by means of the pipes F F', having 90 the valves H', by which the ovens can be supplied with hot gas for combustion when they are being heated. The hot gas for combustion may be supplied directly from one heater to the other by means of the pipe I', 95 having regulating-valve K' extending from the combustion-chamber of one gas-heater to that of the other. The valve K', in this case, after being properly set, always remains open. The combustion-chambers B⁶ are also connected 100 with cold-gas-supply main T by means of pipe V, having valve X. The gas-heaters are connected with the chimney D', means of the connection P, valve R, horizontal pipe W, having valve A⁵ and connecting with vertical pipe B⁶ 105 and horizontal pipe C'. They are also connected with the cold-gas-supply main T, for the purpose of receiving the gas to be heated by means of the pipe S, valve R, and connection P.

In practice at least two gas-heaters are used, in combination with at least two ovens for heating the blast, but in case where the apparatus is used for heating anything but air it will be necessary to use a set of two supplementary ovens to heat the air for combustion and having an additional hot-air main and connections, if it is desired to have hot air for burning the combustible gas.

When heating a blast of air and heating both 120 the ovens and heaters by burning hot gas with hot air the operation is as follows, all valves being closed: In oven B' open the cold-blast valve L², by which cold air is admitted and passes through the compartments and series of 125 flues to the combustion-chamber, then open the hot-blast valve C², allowing the air to pass into the hot-blast main L', and thence to the blast-furnace. Then in gas-heater A' open the cold-gas valve R and the hot-gas-connection valve 130 H', by which means we have gas admitted and passing through the separate compartments

and flues and into the hot-gas main E'. Then in oven B open the chimney-valve I² and the hot-gas-supply valve N², to admit gas into the combustion-chamber, and open the valve R² on 5 the pipe P², and valves U² on pipe T², to supply air for burning the gas, which is then ignited. The regulating-valves R² and U², when properly set, always remain open. Then in gas-heater A open the chimney-valve A⁵, and the 10 valves T' on the pipes R', to supply air for combustion. Then open the hot-gas-supply valve H', to admit combustible gas from the main E', and ignite; or the gas can be supplied directly from one heater to the other by means 15 of the pipe I', by opening the regulating-valve K', which, when properly set, remains open. The products of combustion pass through the compartments and flues to the chimney D' by pipes W, B², and C'. Now, after a longer or 20 shorter interval—that is, until both the oven B and gas-heater A have become heated to a sufficient degree—the ovens and heaters are reversed at the same interval, or the ovens at one time and the heaters at another, depending 25 on the wishes of the operator. Supposing that the reversal is at the same interval, proceed as follows: In oven B close the hot-gas valve N² and the smoke or chimney valve I², and open the cold-blast valve L², and open the 30 hot-air or blast valve C², by which means we have hot air passing into main L'. Then in oven B' close the hot-blast valve C² and the cold-blast valve L², and open the chimney-valve I², and the hot-gas valve N², and the 35 regulating-valves U² and R² on the pipes T² and P², which, when properly set, always remain open, both when the oven is heating blast or being heated by burning gas. Then in gas-heater A close the air-supply valves 40 T' and the hot-gas-supply valve H', if combustible gas is admitted that way. Then close the chimney-valve A⁵ and open the cold-gas-supply valve R and the gas-connection valve H, thus introducing hot gas into 45 the hot-gas main E'. Then in gas-heater A' close the cold-gas-supply valve R and open the chimney-valve A⁵ and close the hot-gas-connection valve H and open the hot-gas-supply valve H', if gas for burning is supplied in 50 that way, and then open the air-supply valves O'. In the subsequent reversals proceed in the same way, the length of the intervals between which, after the apparatus is in full operation, depends on the time that it takes for 55 the ovens and gas-heaters to become sufficiently heated and that required for them to part with their effective heat. It also depends upon the temperature of the blast desired. Before the first reversal, oven B and gas-heater 60 A were heated by means of cold gas burned with cold air, but after the first reversal the gas passing through the gas-heater A and the air passing through the oven B are both heated several hundred degrees; hence gas-heater 65 A' and oven B' are being heated by burning hot gas by hot air, thus acquiring in an equal

interval a temperature several hundred degrees hotter than oven B and gas-heater A did by burning cold gas with cold air. Now, after a second reversal we have the gas-heater 70 A' and oven B' supplying air and gas several hundred degrees hotter than heater A and oven B did, and consequently heater A and oven B in an equal interval, by the combustion of this more highly heated gas with the 75 more highly heated air, become several hundred degrees hotter yet, and after reversal furnish still hotter air and gas, and so on after each reversal hotter gas is burned with hotter air, thus developing a temperature of blast 80 which is only limited by the resistance of the refractory materials composing the apparatus.

By properly proportioning the quantity of blast to be heated to the size of the ovens and gas-heaters and quantity of gas to be heated, 85 and regulating the intervals between reversals, any temperature of blast can be maintained provided it be not beyond the resistance of the materials, or the temperature may be varied by the operator as demanded by the exigencies of the metallurgical operations.

The gas-heaters are all so arranged that they can be supplied with cold gas for combustion from the main T by means of the branch or pipe V having the valve X. In this case the 95 valve K' on the connecting-pipe I' is closed, and the method of operating is the same as when the gas for combustion was obtained from the hot-gas main E by means of the valve H', excepting that the valve X' is used 100 in place of valve H'. If it is desired a mixture of hot and cold gas can be used by having the valve K' partially opened.

The ovens are all so arranged that they can burn cold gas in connection with hot air. The 105 cold gas is supplied from the cold-gas main T by the branch V², provided with the valve W², and in the reversals the valve W² is substituted for the hot-gas valve N², but otherwise it is the same. They can also be run on a 110 mixture of hot and cold gas, and in this case it is necessary to use both of the valves W² and N² to admit the gas.

When using cold gas the gas-heating part of the apparatus may be done away with, or held in reserve in case an intensely-hot blast is desired, as when the blast-furnace is working cold and badly.

What I claim is—

1. In a regenerative hot-blast apparatus for 120 heating a blast of air, gases, or vapors to be supplied to metallurgical furnaces, the combination, with the principal ovens for heating the blast, of one or more gas-heaters or supplementary ovens for heating the combustible 125 gas prior to its being burned in the principal oven and the gas-heaters, substantially as and for the purpose set forth.

2. In a regenerative hot-blast apparatus, substantially as described, the combination, with 130 the ovens, of one or more gas-heaters and a hot-air main connected to said ovens and gas-

heaters, whereby a forced blast of hot air may be supplied to the burning gas therein to intensify their combustion and thus heat them most intensely, and also to increase the flow 5 of the products of combustion through the oven and gas-heater and thus decrease the chimney-draft necessary, essentially as and for the purpose specified.

3. In a regenerative hot-blast apparatus, substantially as described, the combination, with the ovens, of a hot-air main connected to said ovens, whereby a forced blast of hot-air may be supplied to the burning gases to intensify the combustion therein and most intensely heat them to increase the flow of the products of combustion and to lessen the chimney necessary, essentially as and for the purpose specified.

4. In a regenerative hot-blast apparatus, the combination, with the ovens, of the gas-heaters, hot-air main, and hot-gas main connected to said ovens and gas-heaters, whereby intensely-hot combustible gas may be supplied to the ovens and gas-heaters to be burned 25 therein by a forced hot-blast to heat the ovens and gas-heaters, substantially as and for the purpose specified.

5. In a regenerative hot-blast apparatus, the combination, with the ovens, of the gas-heaters 30 and a hot-gas main connected to said ovens and gas-heaters, whereby intensely-heated combustible gas may be supplied to said ovens and heaters to be burned therein, and thereby intensely heat the said oven, substantially as and for the purposes specified.

6. In a regenerative hot-blast apparatus, the combination, with the ovens, of the gas-heaters and the cold-gas connection, whereby combustible gas may be heated and supplied to 40 ovens and gas-heaters, and an intensely-heated blast supplied to the furnace, substantially as and for the purpose specified.

7. In a regenerative hot-blast apparatus, the combination, with the ovens B B' and the gas-heaters A' A, of the cold-gas main T and 45 branches S, V, and V', and their valves, and the hot-gas main E', and branches F' and G' and their valves, and the hot-air main L', and the several connections T', T'', R', P', and N', and their valves, and the smoke-main leading 50 to the chimney D', whereby air and gas for combustion may be supplied to said heater for burning therein, or combustible gas may be passed through said heater, by which means 55 it is intensely heated prior to passing to the ovens and gas-heaters to be burned therein, substantially as and for the purpose specified.

8. In a regenerative hot-blast apparatus, the combination, with the ovens B B' and gas-heaters A A', the cold-gas main T and branches, 60 the hot-gas main E' and branches, the pipes G' and K', and the pipes M' U' and their respective valves, and the main L', whereby an

intensely-heated blast may be supplied to a metallurgical furnace, substantially as and for 65 the purpose specified.

9. In a regenerative hot-blast apparatus, the combination, with the respective combustion-chambers of the ovens B B', and gas-heaters A A', and the hot-air main L', of the perforated 70 air-cylinders O' and blocks S' within the combustion-chambers, and their connecting-pipes R', T', and N', having suitable valves, whereby a forced blast of hot air may be supplied to the respective combustion-chambers 75 of the ovens and heaters, substantially as and for the purpose specified.

10. In a regenerative hot-blast apparatus, the combination, with the ovens B B' and the hot-air main L', or parts in free communication 80 with it, the perforated air-cylinders O' and blocks S' within the combustion-chambers, and their connecting-pipes R' and T', provided with suitable valves, substantially as and for the purpose specified.

11. The herein-described rectangular ovens and gas-heaters, each divided into two parts, forming, respectively, combustion-chambers and regenerators, the former being equal in length to the greatest width of the ovens or 90

heaters, and which ovens or gas-heaters are also divided into independent compartments, the regenerator portions of said compartments being provided with vertical flues arranged in sets, forming a decreasing series from the combustion-chambers to the cool end of the ovens or gas-heaters, whereby the products of combustion and blast or gas to be heated are evenly distributed, and the capacity of each set of 95 flues and surfaces and materials are proportioned to the decreasing volume of the cooling and contracting products of combustion when the ovens or gas-heaters are being heated, and, conversely, when the ovens or gas-heaters are heating the blast or gas the capacity of each 100

set of flues and surfaces and materials are proportioned to the increasing volume of the blast or gas as it becomes heated, thus producing a uniform velocity throughout the ovens or gas-heaters in each case and very greatly increasing 105 the efficiency of the apparatus, essentially as set forth.

12. The combustion-chambers D' of the ovens and gas-heaters, having the lower parts connected by the walls E', and in which are 110 placed, at their angles, the perforated air-blocks S', and at the same level the perforated central air-cylinders O', substantially as described.

In testimony whereof I have hereunto set my hand in the presence of two subscribing 115 witnesses.

JOHN C. LONG.
